UNITED STATES PATENT OFFICE.

JOHN LEONARD SCOBAY, OF LOUISVILLE, KENTUCKY.

MAKING OF MATTRESSES AND THE LIKE.

Application filed December 15, 1927. Serial No. 240,143.

The present invention relates to a process for manufacturing mattresses or like articles by filling the same with fibers directly as they are discharged from the mills used in the cotton industry or similar industries. The 5 invention more particularly relates to a process in which one or more of the usual steps in the handling of the fibrous material in the manufacture of the mattresses is eliminated and an improved product is produced. The apparatus for carrying out the 10 present process is to be understood as forming a part of this invention.

In the procedure heretofore practiced in 15 the manufacture of mattresses it was customary to tightly bale the filling material and transport the same to a mattress factory where the covering was removed from the bale and the filling material subjected to a 20 separate picking process in order to unpack the fibers contained in the bale which in effect was a step to undo that work which had been done when the bale was formed. After the fibrous material was subjected to 25 the preliminary treatment of picking, it was cleaned in some way, such as for instance, by blowing or beating with a view to removing dust and other particles of foreign material therefrom.

30 The present invention is particularly advantageous for use in connection with the known processes of manufacturing oil from cotton seed. In the manufacture of oil from cotton seed the usual practice is to first pass the seeds through a machine known as a 35 linter, said machine removing the small particles of lint which are not removed by usual ginning processes. The small particles of lint thus recovered are run through a condenser also of the usual construction, and this 40 condenser partially cleans the lint and forms a batting of the fibers in the form of a fluffy mass. Formerly, the fluffy mass formed by the condenser was passed directly to a press 45 wherein it was formed and bound into bales for shipment.

The object of the present invention is to 50 eliminate the necessity of baling and subsequently unbalancing the fibrous filling material so that the material is never tightly compressed at any time but is left in a loose, fluffy condition from the time of its initial recovery until it is placed in its ultimate enclosure. The invention also contemplates the 55 elimination of numerous steps in the han-

dling of fibers used in the manufacture of mattresses and the like in addition to maintaining the fibers in a non-compressed condition which results in the formation of a downy mass.

It is a further object of the present invention to provide a process wherein the fibrous filling material is taken directly from the apparatus in which it is recovered, and by a continuous operation in a single apparatus 60 prepared and placed directly into the ultimate enclosure.

As the present invention is particularly adapted for use in connection with cotton oil mills the operation will be described in 70 this connection. However, it is to be understood that this invention is not limited to use with cotton oil mills and that it is illustrated in connection with such mills merely for the purpose of convenience.

75 The apparatus illustrated is the type preferred to be used in carrying out the present process but it is to be understood that other forms of apparatus may be employed which will permit the efficient practice of the process. As stated, the preferred form of apparatus is illustrated in the accompanying drawings, wherein—

Figure 1 is an illustration of the apparatus showing the complete assembly.

Fig. 2 is a plan view of a portion of the apparatus adjacent the inlet end with a part thereof broken away, said view being taken on line 2—2 of Fig. 1.

Fig. 3 is a sectional view taken on the 90 line 3—3 of Fig. 1.

Fig. 4 is an elevation of a portion of the apparatus adjacent to the outlet end with parts broken away for the purpose of illustration, taken on line 4—4 of Fig. 1.

Fig. 5 is a plan view of the apparatus showing the arrangement of the various parts.

Fig. 6 is a sectional view taken on the line 6—6 of Fig. 3.

Referring to the drawings in detail, the 100 numeral 1 designates a cotton condenser illustrated conventionally. Arranged adjacent the outlet of the condenser 1 is the inlet of a suction pipe 2, the suction through the pipe being created by means of a fan 3. The fan 105 3, in addition to creating the suction through the pipe 2, causes a blast of air to be discharged through a pipe 4, which pipe is in turn connected to a dust collector 5 of the so-called cyclone type having associated there- 110

with a distributing apparatus 6. The suction pipe 2, adjacent its inlet, is of a rectangular funnel shape formation as indicated by the numeral 7, and the extreme inlet end thereof is arranged in close proximity to the outlet end of the condenser 1, but a sufficient distance therefrom to permit the commingling of the outside air with the material discharged from the condenser. The funnel shaped portion 7 of the suction pipe extends horizontally from its point of inlet with its upper and lower walls substantially uniformly spaced from one another and the vertical walls thereof gradually converging toward one another to thereby reduce the cross sectional area of this pipe. At the reduced end of the portion 7 the pipe takes a smooth right angular bend as indicated at 7^a and merges into a rounded section 8 of increased cross sectional area which tends to permit expansion of the fibrous material being drawn through the pipe so that it will be in a somewhat fluffy condition as it passes into a vertical portion of the section 8 and move downwardly therethrough. Arranged at the lower end of the vertical portion of section 8 is an enlarged enclosure 9 provided with a foraminated plate or screen 10. A sliding door 11 is positioned in one side of the enclosure 9 for the purpose of controlling the draft through the pipe 2. By the arrangement of the sliding door 11 in the enclosure 9 the fan 3 may be operated at a speed necessary to provide a desired blast through the pipe 4 without causing the suction through the pipe 2 to be accordingly increased. The enclosure 9 has arranged, at the lower end thereof, an outlet which has secured thereto a removable cover 12 in order that any heavy material or foreign matter that may pass through the foraminated plate 10 can be removed. The fan 3 is provided with a housing 13, which housing has a central opening that permits communication between the housing and the enclosure 9 through the medium of a pipe 14.

The fan 3 is of the conventional motor driven type in which the blades 15 thereof are mounted within the housing 13 and extend radially from a shaft of an electric motor, which shaft likewise extends into the housing.

The pipe 4 above referred to is secured to the housing 13 and extends upwardly therefrom at an angle to the vertical, and the upper end of the pipe 4 is secured to the casing of the dust collector 5 adjacent the upper end thereof which causes the fibrous material, as it is blown through the pipe 4 by the fan 3 to be discharged into the collector 5. There is a foraminated funnel shaped element 5^a arranged within the lower portion of the dust collector 5 and to this element the distributing apparatus 6 is attached. Any light

fibrous material as it is discharged from the pipe 4 separates from the fibrous material and is discharged outwardly through an outlet of the dust collector indicated at 16.

The distributing apparatus indicated at 6 is in the form of two conductors or branches 6^a and 6^b. A hinged door section 6^c is mounted upon a pivot at a point adjacent the point of connection of the two branches 6^a and 6^b so that it can be swung to close either one or the other of the branches while permitting the opposite branch to remain open for directing the fibrous material as it settles from the dust collector through one or the other of the branches. By having the swinging door 6^c pivoted at its lower end the door will be maintained in either position to which it is set by means of gravity. The swinging door 6^c is adapted to be moved from one position to the other by means of a handle 6^d which is arranged exterior to the wall of the distributing apparatus.

In carrying out the process in the apparatus above described, the fibrous filling material after it has been removed from the cotton seeds by the linter, is passed into the condenser 1, whereupon the various small particles of lint are formed more or less into a fluffy mass. This fluffy mass is discharged from the condenser at a point directly in advance of the funnel shaped portion 7 of the pipe 2. As this mass projects from the condenser 1 the inrushing air, which is drawn into the funnel shaped portion 7 by the fan 3, tends to separate the mass into individual fibers and permits the heavier foreign matter contained in the mass to drop downwardly out of the mass during the separating action. As the fibers are drawn along by suction through the funnel shaped portion 7 there is a tendency for such fibers to be arranged in more or less parallel formation and as the fibers proceed through this portion of the pipe 2 they are brought into a somewhat closer relation, whereby, when the fibers are passed around the smooth right angular bend 7^a into the circular portion 8 of the pipe there is a tendency for the mass to expand and permit the separation of further foreign matter therefrom. The separating action is continued as the fibers pass into the vertical portion of the pipe 8 where they are drawn violently downwardly in this expanded arrangement but still in a more or less parallel condition. As the fibers reach the lower end of the vertical portion of the section 8 whatever heavy foreign matter that is still in the mass is removed through the foraminated plate 10 and the fibers substantially free from heavy foreign matter are passed through pipe 14 into the fan housing 13 where by means of fan 3 they are violently agitated, beaten and fluffed and blown upwardly through the pipe 4 to the point of discharge into the dust separator 5 where the remaining foreign

matter which is lighter than the fibers is separated from the fibers and discharged through the outlet 16, and the fibers are permitted to settle into the element 5^a in the lower portion of the dust collector 5. The holes 5^b in the element 5^a allow air to circulate through the fibrous mass immediately before it is placed into its ultimate container. From the dust collector 5 the fibers are directed through either branch 6^a or 6^b of the distributing apparatus 6. A mattress tick is adapted to be held upon the discharge outlet of either the branch 6^a or the branch 6^b of the distributing apparatus whereby, when the tick or other receiver becomes filled the opposite branch can be utilized during which time the filled receiver can be removed and an empty receiver substituted therefor.

As previously stated, the door 11 may be opened to any degree desired, so that the suction created in the pipe 2 may be diminished independent of the speed of the fan 3.

I claim—

25 1. A process for making mattresses and the like wherein the material to be used as a filler is condensed, then subjected in its condensed condition to a violent separating action by drawing air therethrough, while at the same time allowing the material to pass over a space open to the atmosphere to permit the separation of heavy foreign material therefrom, again condensing the material in a manner so that the particles thereof are arranged in a uniform order, thereafter again expanding the material to permit further separation of foreign material, and then subjecting the fibers to a violent beating and fluffing action.

40 2. A process for making mattresses and the like wherein the material to be used as a filler is condensed, then subjected in its condensed condition to a violent separating action by drawing air therethrough, while at the same time allowing the material to pass over a space open to the atmosphere to permit the separation of heavy foreign material therefrom, again condensing the material in a manner so that the particles thereof are arranged in a uniform order, thereafter again expanding to permit further separation of foreign material, subjecting the material to a violent beating and fluffing action, and then blowing the material in order to remove the lighter foreign materials therefrom.

55 3. A process for making mattresses and the like wherein the material to be used as a filler is condensed, then subjected in its condensed condition to a violent separating action by drawing air therethrough while at the same time allowing the material to pass over a space open to the atmosphere to permit the separation of heavy foreign material therefrom, again condensing the material in a manner so that the particles thereof are arranged in a uniform order, thereafter again expand-

ing to permit further separation of foreign material, subjecting the material to a violent beating and fluffing action, blowing the material upwardly in order to remove the lighter foreign material therefrom, and allowing it to settle downwardly into the container which it is to fill. 70

4. A machine for filling mattresses and the like comprising a pipe having a funnel shaped section, the portion of greatest cross sectional area of the funnel shaped section forming an inlet to the pipe, said pipe at the portion of the funnel shaped section of smallest cross sectional area gradually merging into a rounded portion thereof, a fan having a housing, said rounded portion connecting with the fan housing, another pipe leading from the fan housing to a large receptacle, said receptacle having an outlet adjacent its top and a second outlet adjacent the bottom thereof. 75 80 85

5. A machine for filling mattresses and the like comprising a pipe having a funnel shaped section, the large end of the funnel shaped section forming an inlet to the pipe, said pipe having a second section connected to the small end of the funnel shaped section, an enclosure, said second section leading into said enclosure, a fan having a housing, the enclosure connecting with the fan housing, a second pipe connected to the outer portion of the fan housing and extending upwardly, a large receptacle connected with the upper end of the second pipe, said receptacle having an outlet adjacent its top and a distributing means connected to the bottom thereof. 90 95 100

6. A machine for filling mattresses and the like comprising a pipe having a funnel shaped section, said section extending horizontally from its point of inlet and having upper and lower walls substantially uniformly spaced 105 from one another, and vertical walls gradually converging toward one another to thereby reduce the cross-sectional area, a second section of said pipe of slightly larger cross sectional area than the smallest cross sectional area of the funnel shaped section and into which the small end of the funnel shaped section merges, said second section forming a smooth right angular bend and extending vertically downward, an enlarged enclosure connected to the lowermost end of the second section, a fan having a housing, the enlarged enclosure being connected to said fan housing centrally thereof, a second pipe connected to the outer portion of the fan housing and extending upwardly, a large receptacle having an outlet in its top and a distributing means arranged adjacent the bottom thereof connected to the upper end of said second pipe. 110 115 120 125

7. In a machine for filling mattresses and the like, means for collecting and concentrating the filling material into a more or less uniform mass, said means having an outlet, a pipe having a funnel shaped section, the 130

inlet of which is arranged adjacent the outlet of said above mentioned means, said funnel shaped section extending horizontally therefrom, the pipe at the end of the funnel shaped section gradually merging into a rounded portion of slightly larger cross sectional area than the smallest cross sectional area of the funnel shaped section, said rounded portion forming a right angle bend and extending vertically downwardly, an enlarged enclosure connected to the lower extremity of said rounded portion of the pipe, said enclosure having a sliding door in a wall thereof, an outlet at its bottom having a removable cover and a foraminated plate extending angularly across its interior, a fan having propelling means, blades and a casing, said enlarged enclosure being connected by a pipe with the fan casing centrally thereof, a further pipe connected to an outer extremity of the fan casing and extending angularly upwardly, the uppermost portion of said last-mentioned pipe connected to a large receptacle having an outlet in its top and a foraminated funnel shaped element arranged in its bottom, distributing means attached to the reduced end of the funnel shaped element comprising a pipe having two branches and a door pivoted at its lower end adjacent the point of connection of the two branches, and means connected with said door and extending to a point exterior of the outer walls of the distributing apparatus, whereby the said door may be actuated.

35 8. A continuous process for making mattresses in connection with cotton oil mills, in which lint obtained from cotton-seed after the original ginning process is utilized, which

comprises partially cleaning and concentrating the lint in a condenser, drawing the partially cleaned lint by suction across an unrestricted opening to loosen the fibers and to remove part of the foreign matter from them, again concentrating the lint by sucking it through a pipe of gradually reduced cross-sectional area, expanding it and allowing further settling out of foreign matter to take place, then beating and fluffing the lint and blowing it into a receptacle wherein it is further separated from dust and allowed to settle to the bottom, and passing it from said receptacle bottom into mattress ticks.

9. The process for making mattresses from lint which has not been baled which comprises taking the lint directly from the machine wherein it is separated from cotton seed and condensing it, then subjecting it to a cleaning operation, and depositing the clean lint in a mattress tick.

10. The process for making mattresses from lint which has not been baled which comprises taking the lint directly from the machine wherein it is separated from cotton seed and condensing it, then subjecting it to a cleaning operation while under suction, and depositing the clean lint in a mattress tick.

11. The process for making mattresses from lint which has not been baled which comprises taking the lint directly from the machine wherein it is separated from cotton seed and condensing it, subjecting it to a cleaning operation while under suction, beating and fluffing it, and depositing the clean lint in a mattress tick.

In testimony whereof I affix my signature.
JOHN LEONARD SCOBAY.
